TELEPHONE MOUNTING SHELF

Richard Dale Gibson, Indianapolis, Ind., John Neil McGarvey, Drexel, Pa., and Kenneth Burton Woodard, Indianapolis, Ind., assignors to Bell Telephone Laboratories, Incorporated, Murray Hill, N.J.

Filed Oct. 21, 1970, Ser. No. 25,590

Term of patent 14 years

Int. Cl. D25—99

U.S. Cl. D13—1

FIG. 1

FIG. 2

FIG. 3

FIG. 5

FIG. 4

FIG. 1 is a perspective view of our new design for a telephone mounting shelf;

FIG. 2 is a front view of the telephone mounting shelf of FIG. 1;

FIG. 3 is a side view of the telephone mounting shelf of FIG. 1, the opposite side being essentially a mirror image thereof;

FIG. 4 is a perspective view of the telephone mounting shelf of FIG. 1 including a sign on the flange along the top edge thereof; and

FIG. 5 is a perspective view of the telephone mounting shelf of FIG. 1 including a lamp on the flange along the top edge thereof.

We claim:

The ornamental design for a telephone mounting shelf, substantially as shown and described.
